COMBINED PLAYGROUND TUNNEL AND SLIDE

Eric A. Holmquist, Malmo, Sweden, assignor to
Trädgardsarkitekt Eric Holmquist AB, Malmo,
Sweden

Filed Apr. 16, 1974, Ser. No. 461,441

Claims priority, application Sweden Oct. 24, 1973

Term of patent 14 years

Int. Cl. D21—03

U.S. Cl. D34—5 E

FIG. 1 is a perspective view of a combined playground tunnel and slide showing my new design; and

FIG. 2 is another perspective view taken from the opposite side.

I claim:

The ornamental design for a combined playground tunnel and slide, substantially as shown and described.
